UNITED STATES PATENT OFFICE

THOMAS ALLSOP AND WALTER W. SIBSON, OF PHILADELPHIA, PENNSYLVANIA, AS
SIGNORS TO THE PHILADELPHIA DRYING MACHINERY COMPANY, OF PHILADEL-
PHIA, PENNSYLVANIA, A CORPORATION OF PENNSYLVANIA.

FABRIC DRIER.

Application filed April 15, 1924. Serial No. 706,650.

This invention relates to fabric driers, and it has more particular reference to machines adapted for treating knitted articles—such as hosiery for example—which are placed

5 upon forms pivotally mounted on a rotary carrier adapted to travel through a drying enclosure whereby evaporation of moisture is thoroughly effected, with incidental shaping of said articles prior to being stripped 10 from the forms.

Hitherto, various types and combinations of instrumentalities have been employed for concurrently drying and shaping knitted articles with a more or less degree of success, 15 but all have been comparatively expensive to construct as well as costly in operation. Our invention, however, aims to overcome prevailing trade and other objections by providing an organization in which the articles 20 to be dried, after being "boarded" upon suitable forms, are automatically and intermittently travelled through the drying enclosure, and similarly discharged therefrom for "stripping".

25 Another object of this invention is the provision of a novel means whereby knitted articles while being dried are concurrently shaped in a manner acceptable to the trade.

Further objects of this invention are to 30 provide an organization of the foregoing character embodying improved means whereby the operations of "boarding" and "stripping" are more expeditiously effected; to circulate the heating medium in a manner 35 conducive of maximum efficiency; to increase the output capacity; and to provide a comparatively cheap and compact drying machine especially useful for drying and shaping knitted articles.

40 With the foregoing and other objects in view as later on noted—or which will be apparent from the following description—our invention consists in certain novel features of construction, combinations and arrangements of parts hereinafter fully described, 45 illustrated by the accompanying drawings, and tersely featured in the appended claims.

While the following description is for a clear understanding of the manner in which 50 our invention may be carried into practical effect, it is to be explicitly understood that various changes in the form, proportions, size and minor details of construction may

be made within the scope of the claims, without departing from the spirit, or sacrificing 55 any of the advantages, of our said invention.

Referring to the drawings:—

Fig. I is a view in elevation of a drying machine conveniently embodying one practical form of our invention. 60

Fig. II is a top plan view of the preceding figure.

Fig. III is a vertical sectional view taken approximately on the line III—III in 65 Fig. II.

Fig. IV is an enlarged sectional plan illustrating the manner in which the several forms are moved out of—and returned into—the drying chamber.

Fig. V is a detail view exemplifying one 70 convenient manner of removably supporting the several forms hereinafter more particularly referred to.

Fig. VI is a fragmentary detail plan of the form-carrying instrumentality or spider; 75 and,

Fig. VII is a similar view of a modified, or built up, type of spider.

In the typified embodiment of our invention illustrated—which is solely by way of 80 example—similar characters of reference designate corresponding parts in all the views.

The drying machine illustrated is particularly adapted as a hosiery drier, and it will 85 be observed that it comprises a cylindrical enclosure, comprehensively designated by the numeral 8, which is supported upon an appropriate framework of standard section verticals 9—9, braced by a transversely 90 located annulus 10 of angular cross-section, at an elevation from the ground to accommodate certain instrumentalities hereinafter specifically described. Thermo-insulated sheet metal panels are secured to the aforesaid framework to constitute the surrounding wall 11—or said wall may be made up as a unit in the well known manner; while it is fitted with a roof 12, and bottom 13, in accordance with conventional practice. 100

Concentric with and upon the roof 12 there is mounted an invert funnel-shaped dome or crown 14, provided with an exhaust outlet 15 under control of a butterfly damper 16, the extended axis 17 whereof is journaled in a bearing standard 18, and fitted 105

with a rock-arm 19 having depending draw-rods 20, 20',—Fig. I—adapted for manipulation in the well known way, to vary the capacity of the exhaust outlet 15 later on again referred to. The funnel-shaped dome or crown 14 and valve exhaust outlet 15, respectively, serve to provide clearance for certain mechanisms hereafter described, and variably control the flow of fresh air through the enclosure 8 by regulating the quantity of moisture laden air exhausted. Obviously, means may be provided in connection with the draw-rods 20, 20' for arresting same at any predetermined position so as to maintain any desired angular position of the damper 16, between the fully open and closed positions, as will be readily understood without further explanation or descriptive illustration.

Conveniently supported co-axially within the cylindrical enclosure 8, as by depending angles 21 secured within the dome or crown 14, is a cylindrical shell—hereinafter termed the air-duct 22, the upper end whereof is partially closed in to afford a top 23 provided with an opening in which is located a fan 24. It is well to here note that the fan 24 rotates in a horizontal plane, with the shaft 25, thereof, journalled in a vertical bearing 26 conveniently supported by transverse angles 27, 27 secured to the underside of the enclosure roof 12 aforesaid. Rotary motion is imparted to the fan 24 by means of a miter gear 28 secured to the shaft 25, meshing with a complementary gear 29 at the inner end of a radially disposed counter-shaft 30 journalled in foot-step bearings 31, 31 mounted on the aforesaid roof 12 and transverse angles 27, 27. The counter-shaft 30 is in turn rotated through a belt drive 32 from any convenient overhead line shaft—not shown—and it is also provided at its outer end with a cone pulley 33 for a purpose later on explained.

Referring more particularly to Fig. III, it will be seen that the air-duct 22 is located in spaced relation with respect to the roof 12 of the drying enclosure 8, thereby affording ample clearance for the free circulation of air in the manner indicated by the arrows on said figure.

Disposed concentric with the air-duct 22 are headers 34, 34 connected by a vertical series of pipes 35, 35 through which heating medium is circulated in the well known way; a supply connection being indicated at 36—Fig. I—and fitted with an appropriate stop valve 37, while a return or drip is shown at 38.

The aforesaid drying enclosure bottom 13—as best seen from Fig. III—comprises an outer annular portion 13^a, and an inner concentric disk portion 13^b which is securely attached by bolts 39 (Fig. IV)—for example—to a rotatable bearer 40 conveniently splined

on a stud shaft 41, journalled in a bearing 42, supported on paralleled transverse angles 43, in turn rigidly secured to the underside of a channeled track 44, the purpose whereof will-hereafter-be fully set forth. Intermediate the rotatable bearer 40 and upper end of the bearing 42—and cottered to the stud shaft 41—there is located a radially armed spider 45 to which the article carrying forms 46 are pivoted by means of supporting arms 47 and stud pins 48. This spider 45, as best understood from an examination of Figs. IV—VI, may comprise a unitary structure reinforced by ribs 49, which is formed with a series of integral arms 50 radially projecting therefrom at equal intervals of ten degrees—for example. These arms 50 are reinforced by surrounding flanges 51 and spur ribs 52 as well as provided at their free ends with a boss 53 affording a journal bearing 85 for the aforementioned stud pins 48. At this juncture it is well to note that the supporting arms 47—as best seen by Fig. V—are conveniently of channel cross-section and upwardly directed undulatory configuration 90 with the lower end fashioned to afford a substantial boss 54 for secure connection to the upper part of the stud pins 48. Integral with the outer upper end of the supporting arms 47 there is provided a flange 55—somewhat inclined over from the vertical—that constitutes a seat for the article-carrying forms 46 which are each clamped thereto by a hinged leaf member 56 and bolts 57.

Attached by the bolts 57 to the flanges 55 and leaf members 56 are sheet metal angles 58, 59 respectively which afford closure for the space 60—Fig. III—intermediate the annular part 13^a and disk portion 13^b, of the drying enclosure bottom 13, whereby 10 said enclosure is substantially sealed against wastage of the drying medium and the escape of noxious moisture-laden air except as otherwise directed. It is to be particularly noted that the angle 58 is disposed in a plane 11 coinciding with the lower face of the lateral flange of the angle 59 for a purpose later on set forth.

In some cases it may be deemed desirable that the spider 45 should be a built-up (instead of being an integral) structure whereby provision is made for varying the capacity of the machine, as well as to accommodate article-supporting forms of different widths and styles. To this end, and as will 12 be best appreciated by reference to Fig. VII, the spider 45 embodies a central portion 61 having a flanged periphery 62, and radial bracing ribs 63. To the flanged periphery 62 we removably attach outrigger 12 arms 64 of channel cross-section having end bosses 65 to which the form supporting arms 47 are pivotally connected, as hereinbefore explained. Thus it will be readily apparent that the intervals between the 11

outrigger arms 64 may be varied as desired, hence further explanation is deemed unnecessary.

The means for rotating the spider 45 and enclosure bottom portion 13^b simultaneously to effect progression of the article-carrying forms 46 intermittently through the enclosure or drying chamber 8 comprises a crown gear 66 rigidly attached at the lower end 10 of the stud shaft 41. Adapted to actuate the crown gear 66 is a single-tooth pinion 67 (for example) at one end of a transverse shaft 68 journaled in spaced bearings 69, 69, supported by cross beams or angles 70, 15 70, in turn attached to the hereinbefore referred to annulus or framework bracing member 10. Intermediate the bearings 69, 69 we spline to the shaft 68 a worm-wheel 71 that meshes with a worm 72 on a transverse shaft 73 journaled in bearings 74, and adapted to be driven, at different speeds, through the instrumentality of a stepped pulley 75 and belt 76 from the cone pulley 33 on the counter-shaft 30. Suitable means 20 25 such as a dog—not shown—or the like, may be associated with the crown gear 66 to prevent back motion; and, instead of employing said crown gear and single-tooth pinion, we may substitute a cam and pawl 30 device to impart intermittent rotation to the spider 45, as will be readily comprehended by those conversant with the art without illustration or further explanation.

To afford ingress and egress for the article-carrying forms 46 into and out of the enclosure 8 respectively, we provide the latter with spaced vertical openings 77, 77', (Fig. IV) in the surrounding wall 11 thereof, said openings being of sufficient dimensions to ensure free passage of the forms 46 without the articles carried fouling the edges thereof.

Referring once again to the rotatable bottom portion 13^b of the enclosure or drying chamber 8, it will be best seen from Figs. II and IV that the same is fashioned around its peripheral edge with a series of teeth 78 in number equal to that of the article supporting forms 46 included in the drying assemblage. These teeth 78 are of somewhat saw-like configuration, that is to say they are fashioned with an arcuate edge 79 —Fig. IV—with which engages a portion of the complementarily curved edge of the lateral flange of the angles 59 attached to each form-supporting arm 47; and an oblique straight edge 80 that engages the inner aligned edges of the clamped together form supporting assemblage components 59, 56 and 55. As best shown in Fig. IV it will be remarked that, when the article-carrying forms 46 are traversing the drying enclosure 8, the angles 58, 59 are moved into slight overlapping relation—as indicated at

“x”—thereby effecting a somewhat Venetian-shutter-like closure of the space 60. It is also noteworthy that the angle 58 is in stepped planar relation with respect to the lateral flange of the angle 59 in order to clear the free ends 81, 82 of the annular bottom portion 13^a. This annular bottom portion 13^a is interrupted to afford—in conjunction with a segmental plate 83—interspaces 84, 85 that permit swinging of the article-supporting forms 46 out of, and into, the enclosure 8 through the vertical openings 77, 77', in a manner and by the means now to be described. The segmental plate 83 it will be noted functions to close in the major interval between the ends 81, 82, and that it overlaps the intermediate teeth 78.

Securely keyed—or otherwise fixed—to the lower end of each stud pin 48 is what may be termed a trip-block 86, of somewhat rectangular configuration in plan but provided with cam portions or laterally projecting teeth *a*, *b*, *c* and *d*, at the angular points thereof. These trip-blocks 86 are of appropriate size to freely traverse the channeled track 44, as will be best understood on reference to Figs. III and IV, and they are functional to effect swinging movement of the supporting arms 47 by cooperation with stops or obstructions, 87, 88, 89 and 90 in a manner best appreciated from the following brief description of the 95 operation of our novel type of fabric drier.

Assuming the drier is, as illustrated, adapted for drying hosiery, and that the spider 45 is rotatable in a counter-clockwise direction, it will be best understood from Fig. IV that, 100 as said spider is revolved with an intermittent movement (as hereinbefore described) when a form 46 approaches the “stripper” operative—who is stationed near the vertical opening 77—the associated trip-block 86 will 105 encounter the first stop or obstruction 87. As the tooth or cam portion *a* strikes and rides over the stop or obstruction 87—thereby imparting a quarter-turn to the form supporting arm 47, the second tooth *b* will be brought 110 into contact with the second stop 88, whereby said arm is swung a further quarter-turn outwardly through the egress opening 77 into the position designated “A” on Fig. IV. In this position the hose is stripped from the 115 form 46 in the well known way. Upon the next intermittent movement of the spider 45—brought about through the instrumentality of the single-tooth pinion 67 and crown-gear 66—the supporting arm 47 is laterally 120 swung into the position designated “B” by the tooth “*d*” on its trip-block 86 engaging the third stop or obstruction 89. At this juncture it is well to note, that the inner wall of the channeled track 44 is cut away intermediate the points 91, 92 to facilitate the turning movements of the trip-block 86 and associated arm 47, just described.

The succeeding intermittent movement of the spider 45, merely transfers the stripped form 46 without any turning motion of the arm 47 to the position designated "C" where 5 it is again clothed with a wet hose by the "boarder"—stationed thereat—in the well known way. The following intermittent movement of the spider 45 carries the clothed form 46 into the position marked "D", by 10 the tooth "c" of the trip-block 86 engaging and riding over the fourth stop or obstruction 90, whereafter it is guided into the position "E" (or that which it retains during transit through the enclosure 8) by its angle 15 piece 59 registering with a radially aligning tooth 78 on the inner rotary bottom-portion 13^b of the enclosure 8. Obviously the progressive course of the several clothed forms 46 through the drying enclosure 8 will be 20 readily understood without further explanation, while it will be similarly apparent that each successive form 46 is subjected to the movements above described intermediate the positions marked "E" on Fig. IV. Incidentally 25 the inner wall of the channeled track 44, is cut away between the points 93, 94 for a like purpose to that referred to in connection with the points 91, 92.

From the foregoing brief summary of the 30 sequence of movements involved, it is thought that the advantages and simplicity of our novel fabric drier will be thoroughly appreciated without further description, but amongst other things we desire to direct attention 35 to the manner in which the article-carrying forms 46 are disposed at an inclination to the vertical, thereby affording greater ease for the operator to remove the dried articles than would obtain were said 40 forms located perpendicularly. Further, our novel clamps 55, 56 provide a simple means whereby forms of different configuration and sizes may be quickly substituted whenever desired. Still further the heating coils 34, 45 55 may be located outside the path of travel of the forms 46, or intermediate them and the drying chamber wall 11. Again, instead of the inner bottom portion 13^b being adapted for rotation, it may be made stationary; in 50 which case the teeth 78 will be dispensed with, whereupon the form clamping device angles 58, 59 would be progressed around the space 60 with intervening small triangular openings of complementary area to said 55 teeth, as will be quite obvious from the preceding descriptive matter; or, they will be suitably configured to overlap and close in said space.

Although we have described our invention 60 in considerable detail, it is to be explicitly understood that the same is not limited thereby, further than as indicated by the appended claims, for the apparent reason our present invention may be embodied in various

other forms without departing therefrom, or sacrificing any of its advantages.

Having thus described our invention what we claim is:—

1. A fabric drier including an annular enclosure through which the articles to be dried are advanced, means intermittently conveying a series of vertically pivoted form-supporting members through said enclosure, and means for laterally swinging said members counter-and-clockwise by substantially equal degrees about their pivots for presentation exteriorly of the enclosure to effect stripping and replacement of the articles. 75

2. A fabric drier comprising an enclosure, means intermittently transporting a series of vertically-pivoted form-supporting arms through said enclosure with capacity for lateral swinging counter-and-clockwise by equal stages to effect egress and ingress at fixed stations, means affording a passage 85 within the enclosure, means for circulating a drying medium longitudinally through and externally of said passage, and means for heating the drying medium. 80

3. A fabric drier comprising a cylindrical 90 enclosure, means for intermittently advancing a series of form-supporting arms through said enclosure with capacity for swinging counter-and-clockwise by ninety-degree stages to effect egress and ingress at fixed 95 stations, means affording a passage wholly within and concentric to the enclosure, and means for circulating a drying medium longitudinally through and externally of said passage. 100

4. A fabric drier comprising a cylindrical enclosure, means for intermittently advancing a series of form-supporting arms through said enclosure with capacity for counter-and-clockwise swinging by ninety-degree stages 105 with a non-swingable interval to effect egress and ingress at fixed stations, means affording a passage wholly within and concentric to the enclosure, means for circulating a drying medium longitudinally through and externally of said passage, and means for heating the drying medium. 110

5. A fabric drier comprising a cylindrical enclosure, means for intermittently advancing a series of form-supporting arms through the enclosure with capacity for progressive swinging egress and ingress at fixed stations, means affording a passage wholly within and concentric to the enclosure, means for circulating a drying medium longitudinally 115 through and externally about said passage, and means for heating the drying medium, said heating means being arranged intermediate the exterior surface of the aforesaid passage and the form-supporting arms. 120

6. A drying machine including an annular enclosure through which the articles to be dried are advanced; means for inter-

- mittently moving a series of vertically-pivoted form-supporting arms through the enclosure; and means operative through motion derived from such advancement to swing said arms laterally counter-and-clockwise, by positive stages, successively about their pivots for presentation exteriorly of the enclosure to permit stripping and replacement of the articles.
- 10 7. A drying machine comprising a cylindrical enclosure embodying an annular passage, means for intermittently advancing a series of vertically-pivoted form-supporting arms through said enclosure with capacity for laterally swinging counter-and-clockwise by equal degrees with a non-swinging interval to effect egress and ingress respectively at definite stations, and means for circulating a drying medium longitudinally through and externally of said passage.
- 15 8. A drying machine comprising a cylindrical enclosure having a funnel-shaped dome at one end thereof for the exhaust of air, means for intermittently progressing a series of form-supporting arms through the enclosure with capacity for lateral swinging egress and ingress at definite stations, means affording a passage wholly within and concentric to the enclosure, means for circulating a drying medium longitudinally through and externally of said passage, and means for heating the drying medium.
- 20 9. A drying machine comprising a cylindrical enclosure having a funnel-shaped dome and exhaust outlet provided with a damper control, means for intermittently progressing a series of form supporting arms through said enclosure with capacity for lateral swinging egress and ingress at definite stations, means affording a passage wholly within and concentric to the enclosure, means for circulating a drying medium longitudinally through and externally of said passage with looped directional flow, and means for heating the drying medium.
- 25 10. A drying machine comprising a cylindrical enclosure having a funnel-shaped dome and exhaust outlet provided with a damper control, means for intermittently progressing a series of form-supporting arms through said enclosure with capacity for lateral swinging egress and ingress at definite stations, a conduit supported in spaced relation wholly within and concentric to the cylindric enclosure, means for circulating a drying medium longitudinally through and externally of said conduit with looped directional flow, and means intermediate the enclosure wall and conduit for heating the drying medium.
- 30 11. A drying machine comprising a cylindrical enclosure having a funnel-shaped dome provided with a damper control, means for intermittently progressing a series of form-supporting arms through said enclosure with capacity for lateral swinging counter-and-clockwise by equal degrees with a non-swinging interval to effect egress and ingress respectively at definite stations, and means for circulating a drying medium longitudinally through and externally of said conduit with looped directional flow, and means for heating the drying medium.
- 35 12. A drying machine comprising a cylindrical enclosure having a funnel-shaped dome and damper control at one end thereof, means providing an annular opening in the opposed end of said enclosure, means for intermittently progressing a series of form-supporting arms having flanges closing the annular opening through the enclosure with capacity of lateral swinging exit and entry at definite locations, a conduit supported wholly within and concentric to the enclosure, means for circulating a drying medium longitudinally through and externally of said conduit with looped directional flow, and means for heating the drying medium.
- 40 13. A drying machine comprising a cylindrical enclosure having a funnel-shaped dome and damper control at one end thereof, means providing an annular opening in the opposite end of said enclosure, means for intermittently progressing a series of form-supporting arms about the annular opening and enclosure with capacity of lateral swinging exit and entry at definite locations, means associated with the supporting arms for substantially closing in the annular opening during progression about the enclosure, a conduit wholly within and concentric to the enclosure, a fan for circulating a drying medium longitudinally through and externally of said conduit with looped directional flow, and means for heating the drying medium.
- 45 14. In a drying machine including an annular enclosure through which the articles to be dried are advanced, means for carrying a series of pivoted form-supporting arms through the enclosure, cam teeth about the arm pivots, and trip means located in the path of movement of said cam teeth to intermittently swing the arms horizontally for presentation externally of the enclosure to permit stripping and re-clothing of the forms.
- 50 15. In a drying machine including an annular enclosure through which the articles to be dried are advanced, the combination of a carrier having a series of pivoted arms supporting article-carrying forms, cam teeth about the arm pivots, means for intermittently rotating the carrier to advance the forms through the annular enclosure, and means cooperative with the cam teeth whereby each pivoted arm is progressively swung

to effect horizontal egress and ingress from and into said enclosure at definite stations.

16. In a drying machine including an annular enclosure through which the articles to be dried are advanced, the combination of a carrier having a series of pivoted arms each of which supports an article-carrying form disposed at an inclination to the vertical, cam teeth about the arm pivots, means 10 for intermittently rotating the carrier to advance the form through the annular enclosure, and means cooperative with the cam teeth whereby the pivoted arms are progressively swung in a horizontal direction to 15 effect exit and entry from and into the drying machine at definite locations.

17. In a drying machine including an annular enclosure through which the articles to be dried are advanced, the combination 20 of a carrier having a series of pivoted arms each of which removably supports an article-carrying form inclined to the vertical, cam teeth about the arm pivots, means for intermittently rotating the carrier to advance the 25 forms through the annular enclosure, and means cooperative with the cam teeth whereby the pivoted arms are progressively rotated in a horizontal direction to effect exit and entry of the forms from and into the 30 annular drying enclosure at definite locations.

18. In a drying machine including an annular enclosure through which the articles to be dried are advanced, the combination 35 of a carrier having a series of pivoted arms to the free ends whereof are clamped article-carrying forms inclined to the vertical, cam teeth around the arm pivots, means for intermittently rotating the carrier to advance 40 the forms through the annular enclosure, and means cooperative with consecutive cam teeth whereby said arms are progressively rotated in a horizontal direction to effect exit from and entry into said annular enclosure at definite locations.

19. In a drying machine including an annular enclosure through which the articles to be dried are progressed, the combination 50 of a radially armed spider and superposed turntable, the latter forming a part end-closure for the drying machine, supporting members pivoted to the free ends of the spider arms, article-carrying forms removably clamped to the free ends thereof, means 55 for intermittently rotating the spider and turntable to progress the forms through the annular enclosure, and means whereby the supporting members are individually actuated to effect exit from and entry into the 60 annular drying enclosure at spaced locations.

20. In a drying machine including an annular enclosure through which the articles to be dried are progressed, the combination 65 of a radially armed spider and superposed

turntable, the latter affording a part end-closure for the drying machine, a supplemental series of upwardly inclined form-supporting members pivoted to the outer ends of the spider arms, each pivot-pin 70 whereof is provided with a trip-block, a channeled track with which the trip-blocks engage to retain the form-supporting members relatively stationary during progression through the annular drying enclosure, means 75 for intermittently rotating the spider and turntable, and means whereby the supporting members are individually swung to effect exit from and entry into the drying 80 enclosure at definite locations.

21. In a drying machine including an annular enclosure through which the articles to be dried are progressed, the combination 85 of a radially armed spider and superposed turntable, the latter affording a part end-closure for the drying machine, a supplemental series of form supporting arms pivoted to the outer ends of the spider arms, each pivot-pin whereof is provided with a toothed cam device, a channeled track 90 through which the cam devices travel to retain the form-supporting arms relatively stationary during progression through the drying enclosure, means for intermittently rotating the spider and turntable, and means whereby the form supporting arms 95 are individually swung to effect exit from and entry into the annular drying enclosure at definite locations.

22. In a drying machine including an annular enclosure through which the articles to be dried are progressed, the combination 100 of a radially armed spider and superposed turntable, the latter affording a part end-closure for the drying machine, a supplemental series of form-supporting arms pivoted at the outer ends of the spider arms, each pivot pin whereof is provided with a toothed cam device, a channeled track affording guidance for the cam devices to 105 retain the form-supporting arms relatively stationary during progression through the drying enclosure, and a series of obstructions associated with the channeled track for imparting a half-turn in one direction 110 to move each form-supporting arm into "stripping" position, a successive quarter-turn into "boarding" position, and a further quarter-turn to drying enclosure progressive position.

23. In a drying machine including an annular enclosure through which the articles to be dried are progressed, the combination 115 of a carrier having a series of pivotal outriggers, removable article-carrying forms attached to the outer ends thereof, means for intermittently rotating the carrier, means for maintaining the form-carrying outriggers relatively stationary during progression 120 through the annular passage, and a series of 125

- associated obstructions adapted to impart a half-turn to each individual outrigger whereby to swing the article-carrying form from enclosure progressive location into "stripping" position, a successive quarter-turn to move the same into "boarding" position, and a further quarter-turn to return said form into the enclosure progressive location.
24. In a drying machine including an annular enclosure through which the articles to be dried are progressed, the combination of a radially armed spider and means affording a part end-closure for the drying machine, a complemental series of form-supporting outriggers pivoted to the spider arms, each pivot pin whereof is provided with a toothed cam device, a channeled track with which the cam devices engage to retain the form-supporting outriggers relatively stationary during progression through the drying enclosure, a series of obstructions associated with the channeled track for individual turning of each outrigger to effect its exit and entry out of and into the drying machine at spaced locations, and opposed angle members carried by the outriggers having arcuately configured lateral portions adapted, when moved into overlapping relation, to substantially seal the annular enclosure aforesaid.
25. In a drying machine including an annular enclosure through which the articles to be dried are progressed, the combination of a radially armed spider and turntable affording a part end-closure for the drying machine, a complemental series of form-carrying outriggers pivoted to the spider arms, each pivot pin whereof is provided with a toothed cam device, a channeled track with which the cam devices engage to retain the form-carrying outriggers relatively stationary during progression through the drying enclosure, a series of obstructions associated with the channeled track for individual actuation of each outrigger to effect exit and entry from and into the drying machine at spaced locations, opposed angle members having arcuately configured lateral portions associated with the form carriers adapted—when brought into registration—to substantially close in the annular enclosure aforesaid, and teeth around the periphery of the turntable patterned to fill in the interspaces between the registering angle members.
26. In a drying machine including an annular enclosure through which the articles to be dried are progressed, the combination of a
- radially armed spider and turntable affording a part end-closure for the drying machine, a complemental series of form-supporting outriggers pivoted to the spider arms, each pivot pin whereof is provided with a toothed cam device, a channeled track traversible by the cam devices to retain the form-supporting outriggers relatively stationary during progression through the drying enclosure, a series of obstructions associated with the channeled track for individual movement of each outrigger to effect exit from and entry into the drying machine at spaced locations, opposed angle members having arcuately configured lateral portions associated with the form-supports adapted—when brought into overlapping registration—to substantially close in the annular enclosure aforesaid, saw teeth around the periphery of the turntable patterned to fit the interspaces between adjoining angle members, and a crown-gear and single-tooth pinion adapted to impart intermittent motion to the spider and turntable.
27. In a drying machine including a vertical annular enclosure through which the articles to be dried are progressed, the combination of a radially armed spider and turntable affording a part end-closure for the drying machine, a complemental series of outriggers supporting vertically inclined article-carrying forms pivoted to the spider arms, each pivot pin whereof is provided with a toothed cam device, a channeled track engaged by the cam devices to retain the article-carrying forms relatively stationary during progression through the vertical annular enclosure, a series of obstructions associated with the channeled track for individual actuation of each outrigger to effect its exit and entry relative to the vertical enclosure at spaced locations, opposed angle members having arcuately configured lateral portions carried by the article-carrying supports adapted—when moved into overlapping registration—to substantially close in the annular enclosure aforesaid, saw teeth around the periphery of the turntable, arranged to fill in the interspaces between the overlapping angle members, and a crown-gear and single-tooth pinion adapted to impart intermittent motion to the spider and turntable.

In testimony whereof, we have hereunto signed our names at Philadelphia, Pennsylvania, this 10th day of April, 1924.

THOMAS ALLSOP.
WALTER W. SIBSON.
